No. 734,415.

PATENTED JULY 21, 1903.

P. GAETH & A. GRIEBEL.

FUEL MIXING AND CHARGE CONTROLLING DEVICE FOR
EXPLOSIVE ENGINES.

APPLICATION FILED AUG. 18, 1902.

NO MODEL.

UNITED STATES PATENT OFFICE.

PAUL GAETH AND ANDREW GRIEBEL, OF CLEVELAND, OHIO.

FUEL-MIXING AND CHARGE-CONTROLLING DEVICE FOR EXPLOSIVE-ENGINES.

SPECIFICATION forming part of Letters Patent No. 734,415, dated July 21, 1903.

Application filed August 18, 1902, Serial No. 120,050. (No model.)

To all whom it may concern:

Be it known that we, PAUL GAETH and ANDREW GRIEBEL, citizens of the United States of America, and residents of Cleveland, county 5 of Cuyahoga, and State of Ohio, have invented certain new and useful Improvements in Fuel-Mixing and Charge-Controlling Devices for Explosive-Engines, of which the following is a specification.

Our invention relates to improvements in hydrocarbon explosive-engines, and the object of our improvement is to provide a simple, efficient, and reliable contrivance for mixing the fuel in proper proportions as to air and 15 gas and to control manually the quantity of fuel (charge) for such engines. Preëminently these improvements are intended for vehicle-motors. We attain these objects of 20 our improvement in a contrivance constructed substantially as shown in the accompanying drawings, in which—

Figure 1 represents a partial longitudinal sectional view of such motor provided with the improvements above referred to. Fig. 2 25 is a partial end and cross-sectional view of the same.

Like letters of reference denote like parts in the drawings and specification.

In the illustration herewith given, A designates the cylinder, B the piston, C the inlet-valve, and D the outlet-valve, of and for an explosive-motor. With the casing E of the inlet-valve we combine or attach a fuel feeding and mixing device, which is contained in 35 the supplementary casing E'. (See Figs. 1 and 2.) By way of branch a fuel is conveyed to the needle-valve orifice b, which intersects with the mixing-valve seat c, the flow of the liquid being under control of the needle-valve 40 F. The mixing-valve G controls both the seat c as well as the orifice b. Air enters from below the seat c. To the needle F is secured a lever H, which is operatively connected with the bell-crank I. The latter lever I is 45 arranged for manual or foot operation and under such adjustment allows the inlet-valve C to open more or less according to the charges required, as presently described. The spring J is applied to hold the valve C normally to 50 its seat d, and said spring is interposed between the casing E and the adjustable nut e upon the valve-stem f. As shown, the lever

I has its fulcrum g upon bracket h, which bracket may be an integral part of casing E or it may have independent connection with 55 some stationary part of the cylinder. The arm i of lever I is bifurcated, as at i', and extends under the nut e, and by means of set-screw j and spring k more or less clearance can be established between the terminal i' of 60 the arm and the nut e above referred to. The arm i of lever I is connected with the foot-lever K by means of rod m. The lever K is pivoted upon bracket n, which, as shown, has secure connection with the vehicle-body. 65 The spring k holds the free arm of lever I upwardly with sufficient force so that normally the suction action of the piston is not able to overcome the resistance of said spring k, and the result is that the valve C can only open to 70 the extent of the clearance which exists between the lever-arm i and nut e.

With the extension i" of lever I and needle-valve lever H is connected the rod o. Thus upon pushing the lever K in direction of the 75 arrow the needle-valve F can be withdrawn at the same time as opportunity is given to the valve C to open to an increased extent—that is, when the arm i of lever I is lowered and the resistance of spring k is removed. 80 Originally the needle-valve F is so adjusted as to admit of a flow of liquid fuel, which is just sufficient for a throttled charge, but as soon as a full or an increased charge is admitted into the cylinder then the needle-valve 85 is caused to recede from the orifice b in order to admit simultaneously an increased flow of liquid or as much as may be required for a proper mixture of air and liquid fuel. Mixing of the air with liquid fuel takes place while 90 the former rushes past the opening c as long as the valve C is held open by the suction action of the piston. By the time the charge reaches the inlet-valve C it takes up a sufficient quantity of liquid fuel to render it explosive and suitable for complete perfect combustion no matter whether the motor is running "light," at full capacity, or intermediate charges. The motor is running light 95 as long as there is no pressure brought to bear 100 against the lever K; but as soon as the operator presses with his foot against said lever then the valve C becomes more or less released from the resistance of the spring k and at the

same time a freer flow of liquid is effected, owing to the receding of the needle-valve F. Obviously the lever I might be arranged or equipped for manipulation by hand. However, in connection with motor-vehicles foot operation is preferable.

What we claim, and desire to secure by Letters Patent, is—

1. In an explosive-motor, the combination with the inlet-valve and its seat, and a spring for normally holding it to its seat, said valve being subject to the suction action of the piston; of a stop independent of the spring located in the path of movement of the valve to limit its movement, said stop being normally held fixed in a predetermined position, a mixing-valve with adjacent liquid-feed, a needle-valve controlling said feed, and means for manually varying the position of said stop and needle-valve in one direction to permit of sudden increase of the charge and speed of the piston.
2. In an explosive-motor, the combination with the inlet-valve and its seat, and a spring for normally holding it to its seat, said valve being subject to the suction action of the piston; of a stop independent of the spring located in the path of movement of the valve to limit its movement, said stop being normally held fixed in a predetermined position; the position of said stop relative to the valve being adjustable, a mixing-valve with adjacent liquid-feed, a needle-valve controlling said feed, and means for manually varying the position of said stop and needle-valve in one direction to permit of an increase of the charge and speed of the motor.

3. In an explosive-motor, the combination with the inlet-valve and its seat, and a spring for normally holding it to its seat, said valve being subjected to the suction action of the piston; of a bell-crank lever having one arm reaching under the head of the stem of said valve and forming a stop therefor; a set-screw and spring retaining the lever normally, holding said stop fixed in predetermined position, a mixing-valve with adjacent liquid-feed, a needle-valve controlling said feed and means for manually varying the position of said stop in one direction to permit of an increase of the charge and speed of the motor.

4. In an explosive-motor, the combination with the inlet-valve and its seat, and a spring for normally holding it to its seat, said valve being subject to the suction action of the piston; of a bell-crank lever having one arm reaching under the head of the stem of said valve and forming a stop therefor; a set-screw and spring controlling the normal predetermined distance between said arm and the head of the valve-stem, a mixing-valve with adjacent liquid-feed, a needle-valve controlling said feed and a foot-lever and rods operatively connected with the free arm of said bell-crank lever and needle-valve lever for manually varying the position of said stop and needle-valve in one direction to permit of an increase of air and liquid charge.

PAUL GAETH.
ANDREW GRIEBEL.
